United States Patent Office.

SAMUEL Z. HALL, OF OSSINING, NEW YORK, ASSIGNOR TO HIMSELF, STARKES W. LEWIS, OF SING SING, NEW YORK, AND ELIAS B. BROWN, OF STONINGTON, CONNECTICUT.

Letters Patent No. 105,070, dated July 5, 1870.

IMPROVEMENT IN COTTON-GINS.

The Schedule referred to in these Letters Patent and making part of the same

To all whom it may concern:

Be it known that I, SAMUEL Z. HALL, of Ossining, Westchester county, in the State of New York, have invented certain new and useful Improvements in Cotton-Gins; and I hereby declare the following to be a full and exact description thereof, reference being had to the accompanying drawing forming part of this specification, in which—

Figure 1 is a representation of a central vertical section of my invention.

Figure 2 is a side view, showing the method of driving the feeding-cylinder, by a belt from a pulley on the saw-shaft.

Figure 3 is a view of the opposite side, showing the method of varying the speed of the carrying-rollers.

Similar letters refer to similar parts in the different figures.

My invention relates to cotton-gins, and consists in certain improvements hereafter described, whereby it is designed to increase the efficiency and lessen the cost of construction thereof.

My cotton-gin is supported by the frame A, upon which rests the hopper B, the sides of which project in front, forming, by means of the cheeks b b, bearings for the shaft of the feeding-cylinder and protection to the ends thereof.

The unginned cotton, having been placed in the hopper B, is carried forward by the rollers D D, in the bottom thereof, toward the feeding-cylinder E.

The foremost of these carrying-rollers d is made somewhat smaller in diameter than the others, with the object of conveying the cotton further under the feeding-cylinder, and thereby preventing the loss of much good cotton with the hulls, pods, and trash, as they fall between this front roller and the feeding-cylinder.

When all of the rollers are made of the same diameter, a great many good locks of cotton fall through, unless the trash-board is moved up very close, and, if this is done, the hard pods, pebbles, &c., are apt to be fed by the cylinder E, with the good cotton, over into the breast of the gin.

The small roller d is designed to obviate all difficulty. The main portion of the seed-cotton rests upon and is lifted from the large roller in rear of it, and such good locks as may not be taken up fall on the small front roller d, whence they are taken by the teeth of the cylinder and fed into the breast. Hence the trash-board may be further removed, and all stones, sticks, and hard substances readily discharged beneath the feeder.

The rollers D D d are connected by gearing, as shown on fig. 2 of the drawing, and are operated by means of pawls P and P' and ratchet-wheels m', attached to the ends of the small roller d and first large roller

D, as shown on fig. 3 of the drawing. The pawls are attached to the lever l, slotted in the end, and operated by the crank-pin k, on the disk K, secured to the end of the shaft of the cylinder E. When it is desired to feed slowly, the lower pawl P is pinned back, allowing the upper pawl P' only to operate in connection with the smaller ratchet-wheel, attached to the end of the small front roller d. The cotton will be fed faster when the lower pawl P is allowed to engage with the larger ratchet-wheel.

The feeding-cylinder E consists of two disks or heads, secured to the shaft e. Bars F and slats G are secured alternately around the heads to form the cylinder. The teeth are driven into the bars, and sharpened before the bars are secured to the heads of the cylinder. The spaces between the bars are filled in with thin slats, narrow interstices being left between for the dust to fall through. Heretofore the feeding-cylinder has been covered with wire-cloth, rendering it necessary, in the construction thereof, to sharpen the teeth after they have been driven into the cylinder. By employing the cheek-pieces b b the length of the cylinder can be increased, so that it will take up cotton at the extreme ends of the rollers. In order to prevent the feeding-cylinder from carrying over bunches so large that they might choke the breast of the gin, the regulating-board H is arranged to slide in grooves formed in the walls of the hopper. This regulating-board may be adjusted in proper position, and then secured by means of a thumb-nut on the end of the rod m, arranged to connect the walls of the hopper. A pulley, h, is attached to the end of the cylinder-shaft, and is operated by a belt from a pulley, v, on the saw-shaft, to which the motive power is directly applied.

The cotton passes from the feeding-cylinder into the breast M, where it is ginned by the saws. The breast M is made adjustable by means of the hinged board n, provided with pins or set-screws z z, arranged to slide in the slots r r, formed in the frame. This hinged bar n is also connected, by means of the pivoted arms or links v v, with the centers s s, below and in rear of the saw-shaft. Hence, when it is desired to throw the teeth of the saws further into the breast, the ribs thereof are moved in a direction downward and backward around the saws, their curved path being regulated by the radial arms or links v v, above described.

R R designate the brushes attached to the cylinder R'. These brushes take the ginned cotton from the teeth of the saws.

Fans L L, of rigid or flexible material, are arranged between the rows of brushes on the cylinder R', by the action of which the cotton is blown out of the gin at the point S."

What I claim as my invention, and desire to secure by Letters Patent, is—

1. The small leading-roller *d*, in combination with the carrying-rollers *D D*, of larger diameter, in the feeding-hopper of a cotton-gin, when constructed and arranged to operate as specified.
2. The feeding-cylinder *E*, when constructed of alternate tooth-bars, *F*, and thin slats, *G*, in the manner specified.
3. In combination with the slotted lever *l*, bearing the adjustable pawls *P* and *P'*, the ratchet-wheels *m*, attached to the two front rollers *d* and *D*, when con-

structed and arranged to vary the speed of revolution, as specified.

4. The adjustable breast *M*, arranged to move downward and backward around the saws by means of the slots *r*, hinged bar *n*, and radial arms *v*, pivoted to centers *s* below and in rear of the saw-shaft, as specified.

SAMUEL Z. HALL.
